UNITED STATES PATENT OFFICE.

CHARLES LOUIS DUBOIS AND CLAUDIUS REYNOLD, OF LAUSANNE, SWITZERLAND.

CIRCUIT CONTROLLER.

Application filed December 16, 1920. Serial No. 431,214.

To all whom it may concern:

Be it known that we, CHARLES LOUIS DUBOIS and CLAUDIUS REYNOLD, both citizens of Switzerland, residing at Lausanne, Canton of Vaud, in the Confederation of Switzerland, have invented certain new and useful Improvements in Circuit Controllers, of which the following is a specification.

The object of the invention is a device which, placed in circuit in an electric plant, cuts off the current as soon as the subscriber endeavours to utilize a greater intensity than that to which he is entitled and for which the apparatus has been regulated. This device automatically restores the current at the end of one or several minutes and comprises an induction coil the plunger core of which is kept outside the coil by a spring the tension of which can be regulated according to the maximum intensity of the electric current authorized for the plant in question, and a pole piece intended to close or break the circuit of an automatic time interrupter of known type placed in such a position with regard to the plunger core that it may be attracted by the latter, when in its position at the end of its movement under induction.

The accompanying drawings show a constructional form of the invention, by way of example.

Fig. 1 is a front view of the apparatus.

Fig. 2 is a view from above of the top part of the apparatus.

Fig. 3 gives separately and viewed from above, the interrupter device.

Fig. 4 is a plan view of the pole piece *p*.

Fig. 5 is an axial section of the apparatus given in Fig. 1.

Fig. 6 is a side elevation.

Fig. 7 shows in side elevation a known constructional form of automatic time interrupter combined with the apparatus shown in Figs. 1 to 6.

Fig. 8 is a diagram showing the main and shunt circuits and the clock-work mechanism for restoring the circuit conventionally.

In the form of construction shown, the apparatus comprises a coil *a* (Fig. 1) wound with a thick short insulated wire, in series with the circuit to be controlled.

This coil *a* is wound around the lower part of a tube *b* (Fig. 1). In this tube *b* a soft iron plunger *c* (Fig. 5) can move

freely. This plunger *c* is hung on a chain *d* running on a grooved pulley *e*. The axis of this pulley revolves directly at one end in the frame *f* (Fig. 2) and, at the other end in the axis *k* of the movable dial *g*. The movable dial *g* revolves on its axis *k* (Fig. 2) in the wall of an upright of the frame *f*. It is maintained inside the frame by the pin *h*. A flat spring *i* supported between the frame *f* and the dial *g*, prevents the latter from turning too freely. A spiral spring *j* (Fig. 2) is fixed at one end to the axis *k* and at the other to the pulley *e* (Fig. 2) so that in turning the dial *g*, the spring *j* is more or less set which spring acts by torsion on the pulley *e*. A similar spring *j'*, fixed on the other side of the pulley *e*, is secured at the other end in the frame *f* and serves to counterbalance by torsion, the weight of the chain *d* and of the plunger *c*.

In turning the dial *g* by hand the tension of the spiral spring *j* is decreased or increased. This tension acting by the agency of the pulley *e* and of the chain *d* on the plunger *c* keeps it with more or less force in the top part of the tube *b*, passing beyond the coil *a* Fig. 5. The dial *g* bears indications corresponding to the intensity to be allowed in the plant. As soon as this permitted intensity is exceeded by addition of supplemental lamps or apparatus the magnetic field developed in the coil *a* is sufficient to cause descent of the plunger *c* as far as the centre of the coil *a* where it is stopped by an insulating plug *m* Fig. 5. When the current is cut off, the plunger *c* being no longer subjected to the influence of the magnetic field of the coil *a*, is sharply drawn out of the coil by the tension of the spring *j* as far as the stop plate *n*.

The tube *b* at its exit from the coil *a* is provided with a transverse opening *o* Fig. 5, through which a soft iron pole piece *p* (Fig. 4) can pass. The pole piece *p* is fixed to the end of a rod *q* (Fig. 1) secured at the other end on the axis *r*, by aid of screw *s*. The axis *r* turns between the two uprights of the frame *f*.

The stop piece *t* (Fig. 5) limiting the travel of the rod *q*, in stopping its part passing beyond the axis *r*, keeps the pole piece *p* at a specified distance from the opening *o* of the tube *b*. There is a metal ferrule *u* on the rod *q*. A ring made of insulating material separates this ferrule *u*

from the rod q . The plunger c reaching the centre of the coil a is at its maximum magnetization. This magnetization is then sufficient to attract the pole piece p . When 5 the pole piece p is attracted by the plunger c , the rod q follows its movement by the agency of the axis r revolving in the frame f . This movement has for effect to engage the ring u between the two contacts v Fig. 3, 10 which thereby are connected. The two contacts v are fixed on a block of insulating material w (Fig. 3). On this block w the stop plate n is also fixed, its object being to prevent the plunger coming out of the tube b 15 under the influence of the spring j .

The insulated metal ring u of the rod q connecting the two contacts v puts into circuit an electromagnet a' in a shunt circuit b' the object of which is to cut off the total current 20 of the plant by breaking the main circuit at c' and then restore it automatically in a given time by means of a clockwork mechanism or any other slowing down system shown conventionally in Fig. 8.

25 Fig. 7 represents, as an example, an automatic time interrupter of known type comprising an electro-magnet with clockwork mechanism restoring the current after a moment's interruption.

30 In Fig. 1 x is an interrupter by aid of which the apparatus can be put into circuit or out of circuit and y indicates the current entrance and exit terminals.

The whole device described is enclosed in

a box, which may be locked, not shown in 35 the drawings.

The interrupter x is intended for use when required to temporarily allow a greater intensity of current than that for which the plant is regulated.

40

Claim.

In a circuit controller, an induction coil adapted to be interposed in a main circuit, a plunger core for said coil, a spring operatively connected to said core and normally 45 maintaining it withdrawn from said coil, means for adjusting the tension of said spring in accordance with a predetermined maximum intensity of current, a shunt circuit including electro-magnetic means for 50 breaking the main circuit, and a pole piece arranged in proximity to said plunger core and adapted to be attracted thereby when the magnetic field developed in said induction coil is sufficient to attract said core 55 within said coil, said pole piece being arranged to close said shunt circuit upon being attracted by said plunger core whereby said electro-magnetic means is energized to break said main circuit.

60

In testimony whereof we affix our signatures in presence of two witnesses.
